ANTENNA

Aron Feit, 426 Sandhurst Road, Akron, Ohio 44313

Filed May 18, 1973, Ser. No. 361,522

Term of patent 14 years

Int. Cl. D14—03

U.S. Cl. D26—14 F

FIG. 1 is a side elevational view of an antenna embodying my new design.

FIG. 2 is an enlarged fragmentary front elevational view taken substantially along line 2—2 of FIG. 1.

FIG. 3 is an enlarged fragmentary rear elevational view taken substantially along line 3—3 of FIG. 1.

FIG. 4 is an enlarged top plan view taken substantially along line 4—4 of FIG. 1.

FIG. 5 is an enlarged bottom plan view taken substantially along line 5—5 of FIG. 1.

FIG. 6 is a side elevational view of a modified antenna embodying my new design.

FIG. 7 is a fragmentary rear elevational view taken substantially along line 7—7 of FIG. 6.

FIG. 8 is a bottom plan view taken substantially along line 8—8 of FIG. 6.

FIG. 9 is a side elevational view of another modified antenna embodying my new design.

I claim:

The ornamental design for an antenna, as shown and described.
